United States Patent Office.

THEODORE VANDOREN, SR., OF WASHINGTON, DISTRICT OF COLUMBIA.

Letters Patent No. 72,432, dated December 17, 1867.

IMPROVEMENT IN TAKING THE FORM AND MEASURE OF GENTLEMEN TO CUT COATS AND VESTS.

The Schedule referred to in these Letters Patent and making part of the same.

TO ALL WHOM IT MAY CONCERN:

Be it known that I, THEODORE VANDOREN, Sr., of Washington, in the county of Washington, and in the District of Columbia, have invented certain new and useful Improvements in Taking the Form and Measure of Gentlemen to Cut Coats and Vests; and I do hereby declare that the following is a full, clear, and exact description thereof, reference being had to the accompanying drawings, and to the letters of reference marked thereon, making a part of this specification.

My mode of taking the measure for cutting gentlemen's coats or vests is, by preparing a number of small coats or jackets of the different sizes, as seen at A A¹ A², with the seams of the jackets sewed with the raw edges out at the back and hip-seams. To correspond with each jacket so made, I have patterns, a b c d, cut the exact size of the jackets. When a gentleman desires a coat cut, I place a jacket upon him about the size I think will fit him, always having the same, if anything, a little larger than the person to be fitted. I then take up the loose seams on the jacket, enough for the same to fit neatly around his body, and pin them at the point desired. The jacket is then taken off, and the pattern to correspond with the jacket is brought, and the difference between the gathered-jacket and pattern measured and deducted (if any) from the pattern, and the garment is cut therefrom. It will be seen that a vest can as readily be measured as a coat.

By the mode herein described a measure can be taken in a very short space of time, and a person fitted to more of a certainty than by the tape-measure. This method requires no figures to be placed upon the book, obviating the mistakes that now oftentimes occur. The jackets can be made of any material desired.

Having thus fully described my invention, what I claim as new, and desire to secure by Letters Patent, is—

The use of series of jackets, with the seams thereof formed as herein described, in combination with the patterns, to correspond with said jackets, when said jackets and patterns are used together in the manner described, as a system for cutting gentlemen's coats and vests, herein fully set forth.

In testimony that I claim the foregoing, I have hereunto set my hand, this 8th day of August, 1867.

THEODORE VANDOREN, SR.
